[57] CLAIM

The ornamental design for a top-water fishing lure, substantially as shown and described.

DESCRIPTION

FIG. 1 is a left side elevational view of a lure showing my new design;

FIG. 2 is a top plan of the lure;

FIG. 3 is a bottom plan of the lure;

FIG. 4 is an elevational view of the front of the lure; and

FIG. 5 is an elevational view of the back of the lure.

FIG. 1

FIG. 4

FIG. 2

FIG. 5

FIG. 3
